BAG-CONDITION INDICATOR FOR SUCTION
CLEANERSDonald G. Smellie, Canton, Ohio, assignor to The
Hoover Company, North Canton, Ohio, a cor-
poration of Ohio

Application June 20, 1938, Serial No. 214,679

5 Claims. (Cl. 183—36)

The present invention relates to improvements in bag condition indicators and more particularly to a novel device for indicating the operating conditions of a suction cleaner either by a substantial increase in the pressure within the dirt bag or receptacle, or in the weight of the dirt collected therein.

More recently, it has become the practice to provide suction cleaners with some form of indicator which will enable the user to tell when the dirt bag or receptacle requires emptying and thus avoiding continued operation of the cleaner under conditions that reduce the cleaning effectiveness of the suction system.

For the most part, these indicators have been of the pressure-responsive type and as such respond only to variations in pressure conditions within the receptacle, and while this type of indicator is quite satisfactory and dependable, there may be occasions when an excess pressure may be indicated due to conditions not attributable directly to an excessive amount of dirt within the dirt bag. Then again, the nature of the dirt may vary considerably in different localities and at different seasons of the year, so that the weight of the dirt might well be as much a factor in determining the intervals between emptying as its volume. Hence, it is conceived that in order to indicate the true conditions within a dirt receptacle, the indicator should be constructed to respond to the increase in weight as well as to the increase in pressure due to an excessive volume of the contents.

Therefore, the object of the present invention is to provide an indicator which is responsive to both pressure and weight of contents, depending on which condition predominates.

A preferred embodiment of an indicator of the combined pressure and weight responsive type is disclosed in the accompanying drawings, in which:

Figure 1 is a top plan view of a suction cleaner of the type in which the dirt-laden air is discharged into a filter bag from which the dirt drops by gravity into a removable collecting receptacle, the latter having associated therewith, a combined weight and pressure responsive indicator;

Figure 2 is a general view in side elevation to show the arrangement of the filter bag and removable dirt receptacle in which is incorporated the pressure and weight responsive indicating device;

Figure 3 is an enlarged detailed view in longitudinal section taken through the dirt receptacle on the line 3—3 of Figure 1;

Figure 4 is an enlarged view in cross section taken on line 4—4 of Figure 3;

Figure 5 is a detail view in perspective to show

the connection between the pressure and weight responsive levers and the signal arm;

Figure 6 is a general view in side elevation of a modified arrangement of pressure and weight responsive indicator;

Figure 7 is an enlarged detail view in longitudinal section through the dirt filtering and collecting portion of the cleaner shown in Figure 6;

Figure 8 is a detail view in cross section taken on line 8—8 of Figure 7; and

Figures 9 and 10 are enlarged fragmentary views showing the manner in which the indicating mechanism functions under weight and pressure, respectively.

Referring to Figures 1 and 2, the preferred form of pressure and weight responsive indicating device is applied in conjunction with the dirt collecting receptacle of a suction cleaner in which the dirt receptacle is part of a unitary assembly including the fan chamber and motor housing, all of which rotate about a horizontal transverse axis.

Thus, a wheeled carriage or frame 1 supports the main casing 2 including for the most part the nozzle portion extending transversely across the front of the carriage and a pair of rearwardly extending sections 2a which embrace the ends of a cylindric housing 3 and are suitably supported at their ends by the wheeled frame 1. The housing 3 is journaled at its ends in trunnions 4, 20 4 on the wheeled carriage 1, whereby the entire motor, fan chamber and dirt handling system, including a handle, form a unit rotating about a horizontal transverse axis.

Extending rearwardly from the top of the cylindric housing 3 is a hood 5, rectangular in cross-section and consisting of top and side wall portions, as shown in Figure 4. The hood terminates in a flanged plate 6, which forms the main support for the handle 7 extending at right angles 30 from its upper central portion and also as a mounting for the lower end of a filter bag 8 supported beneath the handle 7.

The hood 5 and its flanged end plate 6 are preferably cast integral with the cylindric housing 3, 35 one end of which forms a fan chamber from which extends an exhaust outlet passage 9, integral with and extending along one side and the top of the hood 5 and terminating in a rectangular-shaped port formed in the plate 6 at one side 40 of the handle and surrounded by a flange 9a, as shown in Figure 4. The filter bag 8 has a separate inlet neck portion 8a which registers with and seats over the flanged port at the outer end of the exhaust passage 9 and immediately adjacent 45 thereto the bag has a considerably larger rectangular-shaped outlet fitting 11, which is removably clamped to the outer face of the plate 6 and in register with a large rectangular-shaped opening 6a just below the handle and the outlet to the bag 50

8. Finally, mounted within the downwardly fac-
ing cavity formed by the hood 5 is a removable
container or receptacle 12 having its open upper
end seating around the underside of the opening
5 or passage 6a through the plate 6 and held in
place by a suitable spring-clip 13.

With the arrangement just described, the dirt-
laden air discharged from the fan chamber enters
10 the filter bag 8 through the inlet neck portion
8a, the velocity of the air stream carrying
the dirt to the upper end of the bag and, upon
losing its momentum, drops by gravity to the lower
end of the bag and eventually is deposited in
the imperforate collecting receptacle 12.

15 Such is the general construction of the cleaner
to which the indicator is preferably applied, al-
though it may be mentioned in passing that a
pressure and weight responsive indicator may be
incorporated into any type of cleaner, although
20 the particular arrangement and method of
mounting may have to be determined according-
ly. Thus, in the present disclosure, the pressure
and weight responsive elements of the indicator
have been included in the removable dirt contain-
25 er 12 and which, under normal operating condi-
tions, assumes an inclined position of approxi-
mately 45° to the horizontal so that it is gradu-
ally filled from the filter bag above, which serves
primarily as an air filter.

30 Referring now to the dirt collecting receptacle
12, the same may be assumed to be a metal con-
tainer open at one end and of a general rectangu-
lar contour. At the bottom of the receptacle 12
is located what might be termed a false bottom
35 in the form of a plate 14 hinged along one edge
to what would be the top wall of the receptacle.
Between the plate 14 and the end wall of the
receptacle is a coiled spring 15 acting to oppose
the movement of the plate under the weight of
40 the dirt in the receptacle. And, to prevent the
dirt from working around the edges of the hinged
plate, a bellows-like wall of rubber or fabric 16
surrounds the edges of the plate and is suitably
attached to the adjacent walls of the receptacle.
45 Also, there is a screened vent 14a at the center of
the plate 14 to equalize the air pressure on both
sides thereof. The plate 14 is supported from the
top wall of the receptacle by a simple form of
hinge as at 17 and extending forwardly there-
50 from and substantially parallel with said top wall
is a finger 17a formed integral with the hinged
plate 14 and projecting substantially at right an-
gles thereto. This finger 17a is free to move in
a limited arc and within a cavity forming a part
55 of the space below the plate 14 and defined in
part by a flanged partition wall 18 supporting the
upper edge of the bellows 16 surrounding the
plate 14.

60 Inserted in the outer wall of the receptacle 12
and immediately above the finger 17a is a circular
diaphragm 19 carrying at its central point a con-
tact pin 19a with its one end portion projecting
inwardly in contact with the finger 17a and its
65 other end projecting outwardly, it being noted
that the diaphragm serves merely as a flexible
wall section supporting the contact pin 19a so
that it can be displaced in the bodily swinging
movement of the hinged plate 14 and under the
weight of the dirt which accumulates in the re-
ceptacle to actuate the signal device, now to be
described:

60 Depending from the underside of the hood 5
just above and midway the length of the recep-
tacle 12, is a bearing bracket 20 consisting of a
pair of arms 20a, 20a, spaced apart and support-

ing a shaft 20b between their ends. On this
shaft are journaled three levers, namely, a rela-
tively long lever 21 extending rearwardly with its
free end in contact with the pin 19a at the center
5 of the diaphragm 19, a forwardly extending signal
arm 22, and a forwardly extending but relatively
short and stubby lever 23. The signal arm 22 is
included between the lever arms 21 and 23 and
all have cylindric hub portions in interlocking
10 connection with each other by an arrangement
of interconnected arcuate notches and dogs, as
will presently be described. This system of levers
is held under the pressure of a torsion spring 24
15 acting on the lever 21 to force it downwardly into
contact with the contact pin 19a of the dia-
phragm 19.

The signal arm 22 extends forwardly toward
the flanged end plate 6 of the hood 5 and termin-
ates just opposite an aperture or window 25 at
one side of the handle mounting. The signal 20
arm 22 has its extreme end portion bent at right
angles to form a target 22a adapted to register
with the aperture when the lever arm is in ele-
vated position. Otherwise, it is held in lowered
or depressed position with the target out of regis-
25 ter with the window. As clearly shown in Figure
3, a light coil spring 26 holds the signal arm 22 in
its non-operative position and against a shoulder
27 positioned just below the aperture 25.

Now, to complete the weight-actuated portion 30
of the indicating device, the hub portion 21a of
the lever arm 21 has a dog 28 projecting endwise
from its inner face and engages an arcuate notch
29 in the opposite face of the hub 22b of the sig-
nal arm 22, this notch being formed by removing
35 a sector of approximately 90° from the hub, as
clearly shown in Figure 5. The dog 28 is sub-
stantially one-half the circumferential dimension
of the notch 29 and as a consequence there is a
40 limited relative rotative movement permitted be-
tween the two levers 21 and 22, the extent of this
movement being substantially an arc of 45°.
Thus, with the lever 21 in its normal position,
as shown in Figure 3, its dog 28 contacts the ver-
45 tical face of the notch 29 so that any movement
of the lever 21 in a downward direction swings
the signal arm 22 with it, although the signal arm
is free to swing in a counter-clockwise direction
and through an arc of about 45°, independently
40 of said lever 21. Hence, it follows that so long
as the hinged bottom plate 14 within the dirt re-
ceptacle 12 is not displaced by the weight of the
contents of the receptacle, the lever arm 21 re-
mains in its normal position and the signal arm
50 in its non-signalling position, as clearly shown
55 in Figure 3. But as soon as the weight of the
contents of the receptacle overcomes the resist-
ance offered by the coil spring 15, the hinged
bottom plate 14 is depressed, thus allowing the
contact plug 19a to be displaced endwise and the
60 lever arm 21 under the tension of the torsion
spring 24, now swings the signal arm upwardly
into the dotted line position, in which the target
at its extreme end comes into register with the
window 25. This target is preferably colored in
65 some bright or contrasting color, such as red or
white and hence is readily observed by the opera-
tor from above.

Now, to complete the indicating mechanism,
the means for actuating the signal arm by varia-
70 tions in pressure within the receptacle 12 includes
the operating lever 23, which has already been
identified as the short forwardly extending lever
journaled on the opposite side of the signal arm
22 from the rearwardly extending lever 21, as 75

clearly shown in Figure 5. The lever arm 23 has the same form of connection with the signal arm 22 as previously described in connection with the lever arm 21, namely, a dog 31 projecting from the inner face of its hub portion 23a and riding in an arcuate notch 32 in the end face of the hub 22b of the signal arm 22. In the same manner also, the signal arm 22 and the shorter lever 23 have a relative angular displacement of about 45°, so that the signal arm can be raised and lowered through the movement of the weight-responsive lever 21 without carrying with it the pressure-responsive lever 23.

Immediately below the outer end of the short lever arm 23 and set into the top wall of the receptacle 12, is an annular diaphragm 33 having a centrally disposed contact pin 33a against which the end of the lever arm 23 bears. This diaphragm 33 is preferably a rubber disc corrugated annularly and capable of being distorted when the pressure within the receptacle exceeds a pre-determined amount, due to an excess of dirt and lime accumulated in the filter bag 8 above.

Thus assuming that such a condition is brought about due to the failure of the operator to empty the bag, and assuming further that the character of the dirt and litter within the bag is comparatively light and therefore does not have sufficient weight to displace the false bottom plate 14, this excessive pressure will distort the diaphragm 33 in an outwardly direction and lift the lever arm 23 sufficiently to raise the signal arm 22 into its signalling position and in the same way that the depression of the false bottom plate 14 operates the signal arm and warns the operator that the receptacle and bag should be emptied of their contents.

But it is important to note that while the weight-responsive element and the pressure-responsive element are both operatively connected with the signal arm, they function independently of each other, which means that whichever condition becomes the more acute, the warning signal will be displayed in response to that condition. In other words, the signal will appear either when there is an excessive weight of contents or excessive pressure due to too large a volume of dirt and litter but yet not heavy enough to be registered by the indicating device.

As previously suggested, the idea of a combined weight and pressure actuated signal mechanism might well partake of different forms and methods of application and for this reason, it is thought desirable to disclose a modified type of pressure indicating device applied to a cleaner of the type having a filter member enclosed within a casing and into which the dirt-laden air is discharged.

Thus, as shown in Figures 6 and 7, a cylindric casing 35 is supported in horizontal position and has a nozzle fitting 36 mounted at its forward end and suitably attached for quick access to the interior of the casing. Extending lengthwise of the forward section of the casing is a cylindric filter member 37 preferably made of a porous fabric. The filter member 37 includes an annular frame 37a at its open end, said frame having a radial flange adapted to be clamped between the marginal portions of the casing and the nozzle fitting 36. The remaining portion of the filter member 37 is supported by a light metal frame consisting of a bar 38 extending lengthwise along the bottom of the casing 35 and hinged at its forward end on a bracket 38a. The outer free end of the bar 38 is supported by a coil spring 39

which in turn rests upon the bottom of the casing 35; and carried at the outer end of the bar 38 is a light metal perforated disc 40 flanged on its inner face and adapted to provide a seat for the outer end of the filter member 37. The disc assumes an upright position at the end of the bar 38, and is connected thereto by a hinged connection at 41, which includes a torsion spring 41a acting to counter-balance any force tending to swing the disc outwardly and in a clockwise direction.

Riveted to a supporting bracket 40a at the top of the disc 40 is a light metal frame 42 generally U-shaped, with its central portion extending transversely of the casing 35. Of the two upright end portions of the frame 42, one provides a long arm 42a inclined slightly in a forward direction, and the other a somewhat shorter arm 42b, extending in a slightly rearwardly inclined direction. Immediately above the bracket 42 is a dome 43 formed in the wall of the casing 35 and having a window or aperture 43a facing in a generally upward direction. The dome forms a semi-circular-shaped cavity opening downwardly into the casing 35 and extending transversely and positioned symmetrically with respect to the center thereof, is a transverse bearing pin 44 on which are journalled a pair of levers 45 and 46, together with signal member 47 positioned intermediate the levers. And finally, there is a torsion spring 48 coiled around the hub portion of one of the levers 46 and having one of its free ends anchored by means of a fixed lug 49 on one side of the dome and its other free end hooked around the forward edge of the signal arm 47.

Now, to avoid an unnecessary repetition of descriptive matter, it may be stated at this point that the relationship and interconnection between the levers 45 and 46 and signal member 47 practically duplicates that employed in the previously described arrangement and for the same purpose, namely, to permit the signal member 47 to be operated by either of the operating levers 45 or 46 but independently of each other. To make this action clear, it is only necessary to point out that one of the operating levers 45 extends forwardly and in a horizontal direction and has a pin and slot connection with the longer arm 42a of the frame 42. The other arm 46 projects downwardly and rearwardly and has a pin and slot connection with the shorter arm 42b of the frame 42.

With this arrangement in mind, it may be assumed that the filter member 37 is empty and the cleaner is put into operation. Under these conditions, the filter member 37 is free to contract slightly in a longitudinal direction under the pressure of the hinged end plate 40 and the parts of the indicating device are positioned so that the signal arm 47 is swung rearwardly just beyond the window opening 43a, as shown in Figure 7. Now, as the dirt-laden air continues to be discharged into the filter member, the dirt is retained, while the air passes through the walls thereof and eventually into the atmosphere and, if the dirt happens to be largely sand or heavy particles, it will form a layer along the bottom of the filter member, or, if the dirt consists largely of lint and other litter, it will gradually fill the filter member and reduce its effective filtering area.

Under the first set of conditions, the weight of the dirt content would in time overcome the support offered by the compression spring 39 to the free end of the hinged bar 38, thus allowing the

same to be depressed bodily. And with the depression of the bar 38, the disc 40 would be displaced in a vertical downward direction with the result that the forwardly extending lever 45 would be pulled downwardly through an angle of approximately 45° and thereby swinging the signal arm 47 into its signalling position beneath the window 43a, as clearly shown in Figure 9. During this movement of the signal arm 10 and the vertical displacement of the frame 42, it will be noted that the other lever 46 retains its normal position with its pin and slot connection with the lever 42b acting in the capacity of a slip joint.

15 But now, let it be assumed that the second set of conditions exists, namely, the filter member becomes filled and the internal pressure builds up to such a point that the filter member is extended longitudinally and against the resistance offered by the hinged end plate 40. As this longitudinal expansion takes place, the end plate swings outwardly and shifts the frame 42 bodily with it, as shown in Figure 10. In this instance, lever arm 46 swings in a counter-clockwise direction through an angle of 45°, and this movement being imparted to the signal arm 47, brings it into register with the window 43a and in the same manner that it was shifted by the weight-actuated lever 45, as previously described. 20 And again, no movement is imparted to the other lever 45 since the pin engaging the longitudinal slot therein simply slides from the forward to the rear end thereof while the lever remains stationary.

30 It may be added that the cleaner embodying the modified form of indicating mechanism is preferably of the type in which the filter unit and dirt collector is on the suction side of the fan, that is, the fan chamber is located beyond the 35 portion of the casing 35 housing the filter member 37. Thus, beyond the closed end of the filter member, is a partition wall 50 having a central aperture 50a forming the inlet to the fan chamber beyond, in which is located the fan 40 51 and a portion of the motor 52 which drives the fan. At the rear end of the casing 35 is an exhaust outlet 53 to the atmosphere consisting of a semi-circumferentially arranged port covered by a screen supporting frame. The motor 45 52 projects beyond the end of the casing 35 and at its rear end is mounted a caster 54 co-acting with a pair of forwardly disposed wheels 55, 55 to support the cleaner. A handle 56 is pivotally mounted at the rear end of the cleaner 50 55 and is provided with a U-shaped bail 56a straddling the extended portion of the motor.

The modified arrangement is perhaps a somewhat simpler form of the two-fold weight and pressure-responsive type of indicator, but obviously the same structural features are to be found in both, as well as the same advantages, namely, that of providing means for warning the operator when the dirt receptacle or filter member should be emptied but not depending 60 on increased pressure as the sole index of conditions on the pressure side of the suction system and which directly affect its cleaning efficiency. And a particular advantageous feature of this arrangement is that while both the weight and pressure-responsive elements have operative 65 connection with the signal member, each functions independently of the other, so that the first to respond to its own peculiar set of conditions within the dirt receptacle will actuate 70

the signal member regardless of what other condition may exist.

Having set forth a preferred and modified embodiment of the invention, I claim:

1. In a bag condition indicator for suction cleaners, the combination with suction-creating means having an exhaust outlet and a dirt receptacle communicating with said exhaust outlet, of means responsive to a predetermined degree of pressure and weight of contents within 10 said receptacle, and a signal member operatively connected with said pressure and weight-responsive means.

2. In a bag condition indicator for suction cleaners, the combination with suction-creating 15 means, of a dirt receptacle communicating with the exhaust from said suction-creating means, a signal member shiftable into and out of signalling position, pressure and weight-responsive elements adapted to function under predetermined pressure and weight of contents within 20 said receptacle, respectively, and means for operatively connecting said pressure and weight-responsive elements with said signal member but independently of each other.

3. In a bag condition indicator for suction cleaners, the combination with suction-creating means and a dirt receptacle communicating with said suction-creating means, of a signal member shiftable into and out of signalling position, a 30 pressure-responsive element operatively connected with said signal member and responsive to predetermined pressure conditions in said receptacle, a weight-actuated member operatively connected with said signal member and responsive to a predetermined weight of contents within 35 said receptacle, and means permitting said signal member to be shifted into signalling position by either one of said pressure and weight-responsive elements functioning independently of each other.

4. In an operating condition indicator for suction cleaners, the combination of suction-creating means, of a dirt receptacle communicating with said suction-creating means and provided with resilient portions, one being yieldable in 45 response to a predetermined increase in pressure within said receptacle and the other in response to the weight of a predetermined amount of dirt deposited therein, a signal member including an oscillating arm mounted adjacent said receptacle, and a pair of levers each operatively connected with said signal arm and one of each having operative connection with said pressure and weight yieldable portions of said receptacle.

5. In an operating condition indicator for suction cleaners, the combination of suction-creating means, a filter receptacle communicating with said suction-creating means and having a yieldable support permitting its displacement in different directions under conditions of predetermined internal pressure and weight of contents deposited therein, a signal member adapted to be shifted into and out of signalling position, and a pair of lever arms operatively connected with said receptacle, one of said lever arms being movable by the displacement of said receptacle under pressure, the other being movable by the displacement of said receptacle under the weight of its contents, both of said levers being operatively connected with said signal member, whereby its movement into signalling position by one is independent of its connection with the other of said levers.

DONALD G. SMELLIE.
